UNITED STATES PATENT OFFICE.

PHILIP H. SHUE, OF OURAY, COLORADO.

ORE-CONCENTRATOR.

SPECIFICATION forming part of Letters Patent No. 681,271, dated August 27, 1901.

Application filed July 11, 1900. Serial No. 23,214. (No model.)

To all whom it may concern:

Be it known that I, PHILIP H. SHUE, a citizen of the United States, residing at Ouray, in the county of Ouray and State of Colorado, have 5 invented certain new and useful Improvements in Ore-Concentrators; and I do declare the following to be a full, clear, and exact description of the invention, such as will enable others skilled in the art to which it appertains 10 to make and use the same, reference being had to the accompanying drawings, and to the letters of reference marked thereon, which form a part of this specification.

This invention relates to improvements in 15 ore-concentrators of that class wherein a rotary member fashioned to constitute a receptacle for the material to be treated is employed, whereby centrifugal force may be utilized to a large extent in effecting the separation of the metals from the ores. Briefly 20 stated, the invention may be classed as a "centrifugal ore-separator."

The present invention is designed more particularly as an improvement on the apparatus shown and described in United States 25 Letters Patent No. 648,088, dated April 24, 1900, issued to myself. While in general principles the machine is related to that type of and is an improvement on the said patented machine, yet the construction in many 30 particulars differs materially therefrom and embodies features which constitute material improvements, resulting in adding great stability, ease of operation, more effective separation, and permitting of the control of the 35 material, so that the separation may be governed readily, according to the character and state of the material being treated.

The objects of the invention are to provide 40 a suitable supporting-frame for the separator, a clear-water-feeding device which will have an independent source, means for adjusting the delivery and collecting tubes so that their receiving-openings may be varied 45 to suit the character of the material being treated, a mechanism for effecting the adjustment which can be operated during the operation of the machine, improved collecting-pans, and in general features and constructions presently to be described.

In the accompanying drawings I have shown

an embodiment of the invention, but desire it understood that various changes and modifications can be made without departing from the nature and principle of the invention. 55

Figure 1 is a longitudinal vertical section showing parts in elevation. Fig. 2 is a side elevation. Fig. 3 is a section on the line xx of Fig. 1. Fig. 4 is a section on the line yy of Fig. 1. Fig. 5 is a section on the line zz of Fig. 1. Fig. 6 is a detail plan of the rotary sleeve, its link connections, and tube-adjusting means. Figs. 7 and 7^a are detail sections of the respective tube-adjusting and clamping mechanisms, and Fig. 8 is a detail perspective view of one of the tubes. 60

A designates a base which is conveniently constructed of four radial arms having a central hub or step-box A'. The base A carries at the end of its arms flanges a , and each arm is perforated to receive an anchor-bolt a' . Secured to the flanges a are uprights B, which are obliquely arranged at a point a distance above their lower ends and extend upward and inward, terminating in vertical sections b , which are bolted to yokes B' B'' , as shown in Fig. 4. 65

C designates the separator, which is conveniently of conical formation, having the bottom C' formed with its outer portion inclining downward and thence directly outward, as at c , forming thereby an annular collecting-channel, the side walls of which are inclined, as shown in Fig. 1. On the outside of the separator near its upper end is formed 80 an integral pulley or belting surface C², forming in addition a shoulder at the top, from the inner portion of which extends the vertical cylindrical bearing c^2 , embraced by the yokes B' and B''. The upper end of the separator 85 above the cylindrical portion c^2 is enlarged and formed into a hopper C³, the upper edges c^3 of which project inward a short distance and constitute lips to prevent the material from splashing out over the edge. Into this 90 hopper the material to be treated is fed, as will presently be described.

D designates the supporting shaft or spindle, passing through the bottom C' and supporting the separator by any suitable means 95 conveniently, such as a jam-nut d , located below the bottom and threaded on the shaft

or spindle. The lower end of the spindle carries a detachable bearing D', having sloping sides and a depending center. This bearing is clamped to the spindle by having an upwardly-extending marginal flange engaging a groove in the end of the spindle, the flange being engaged by the clamping-band d', the tightening of which firmly presses and holds the bearing to the spindle. Other securing means for the bearing may be employed. In the step box or hub A' is placed a steel bearing-block E, having a ball-raceway formed in its upper face and between which and the bearing D' are a series of balls e, thereby forming a ball-bearing for the spindle for the separator. The upper end of the spindle has cast integral therewith a flange or platform D², having inclined upper faces. Below the platform are a series of radial fins d², while above the platform are a series of obliquely-arranged wings d³, extending to the sides of the casing, as shown in my former patent, hereinbefore referred to. The extreme upper end of the spindle is reduced in size, tapered, and formed hollow, as at d⁴, the same terminating at a point below the upper end of the interior of the separator. From the hollow or tubular portion of the spindle extend channels d⁵ outwardly to the sides of the casing, where they communicate with pipes or channels F, formed in the sides of the separator and extending downward to a point near the bottom thereof. To securely unite the spindle with the walls of the separator, screw-bolts c⁴ are employed, passing through the walls of the separator into the platform formed on the spindle. These bolts act in conjunction with the nut d, and by the inclination of the separator and the outer edges of the platform the wings and fins serve as a wedge, firmly binding or impinging against the walls of the separator. With this construction a very rigid connection is formed.

G designates a water-supply tube entering centrally through the upper end of the separator and having threaded engagement with the upper end of the spindle. This tube is centered and held in place by any suitable means, conveniently by set-bolts g, passing through the hopper portion of the separator at different points and radially.

g' designates the funnel or receiver for the supply-tube G, the same being provided with an annularly-extending ring or flange g² to prevent the contents of the funnel or receiver from being thrown out centrifugally during the operation.

By the construction thus far described it will be observed that the machine is provided with means whereby a fresh and independent supply of water can be supplied to the interior of the separator and delivered at the proper points, also that the machine is rigidly supported by the independent frame and that the driving-pulley is made a part of the separator. However, other means for driving the separator may be employed.

Located in the outer walls of the separator at or near the lower edge are the collecting and discharge tubes H, their ends being projected a distance above the bottom of the separator. These tubes have longitudinal apertures h therein, and the tubes are seated in suitable cavities or semicircular grooves formed in the sides of the separator. The upper ends of the tubes are opened and communicate with the lower ends of the water-supply tubes F, so that the discharge of water is directly into the tubes H. To secure the tubes H in their proper adjusted positions, a conical-shaped split nipple J is employed, the same fitting in a screw-threaded aperture formed in the base C'. Through this nipple the tubes H pass and are clamped in position by a nut H', fashioned to engage the outer threaded surface of the split nipple J and force the latter closely against the tube. The nut H' is formed with an annular flange h' at its outer end for purposes presently to be described.

K designates the discharge-tubes for the lighter materials. These tubes are secured by suitable nuts and split nipples, as heretofore described, passing through the bottom C' at points inward or between the center and the walls of the separator. The tubes K extend a considerable distance downward, as shown in Fig. 1.

In such machines it is usually found necessary to vary the size of the receiving-openings of the concentrator or discharge-tubes H, and it is desirable to effect this adjustment or variation without stopping the machine. To provide for such, I have inserted in the tubes H the interior or supplemental tubes L, which extend conveniently the entire length of the tubes H and project a considerable distance below the machine. These tubes L have registering receiving-openings l of a size corresponding with the openings h in the tubes H, so that as the tubes L are set to have the openings register the machine will be set at its full capacity, but by turning the tubes L the size of the openings will be correspondingly diminished. To effect this turning during the operation of the machine, I secure to the tubes a split nipple M, which embraces the projecting end of the tube L and is clamped thereon by the set-nut m, fitting over the nipple. The end of the nipple M has a circular flange m', from which extends a semicircular flange m², from the edge of which extends inwardly a flange m³, thereby forming a semicircular channel or receiving-groove, which when properly arranged engages the flange h' of the nipple H', and thus serving as a means for retaining the tube L in position, but permitting its rotation, the semicircular formation of the retaining-flange being for the purpose of readily applying the retainer to the nipple H' and permitting its removal. From the flange m' of the nipple M extends an arm N, to the outer end of which is attached a link O, which extends inwardly tangentially or at an angle to and

is connected loosely with a collar P, sleeved on the lower end of the spindle D. This collar has an inwardly-extending pin p, which takes into an oblique channel formed in the 5 spindle, the collar being susceptible of independent movement of the spindle, while at the same time being driven or carried by the spindle. To elevate or lower the collar P, I employ conveniently the following mechanism: The collar is provided with an annular channel in which is closely fitted a ring Q, which latter is connected conveniently by rods r to a fork or yoke S, embracing the same and pivotally connected therewith on 10 opposite sides, as shown. The yoke S is pivoted to a stud T on the base A and has an upwardly-extending arm S', forming a bell-crank, to which the actuating-bar U is pivoted, the latter extending outward to and 15 passing through a suitable slot in one of the standards or frames B, the end being threaded and having receiving-nuts u on opposite sides of the bar B, so that its position may be adjusted. By this means it will be seen that 20 by drawing the bar U outward it will raise the inner end of the yoke S, thus elevating the ring R, which in turn elevates the collar P, carrying the same upward on the spindle D, and by virtue of the inclined slot P' and 25 the pin entering therein the collar P will be turned slightly, thus drawing in on the links O, and thereby turning the clamping-nipple M slightly, according to the degree of movement, and rotating the inner tubes L, thus 30 carrying their openings transversely and decreasing the inlet-openings to the tubes. By this means the variation of the discharge-opening may be easily adjusted during the 35 operation of the machine. The tubes K and L discharge into receiving-pans V and V', each of which are inclined gradually and are arranged in a circle. At the lower end of 40 these receiving-pans are any suitable discharge outlets or tubes, (not shown,) through 45 which the material is drawn and conveyed to any suitable place. Any desirable type of valve or gate may be employed for this purpose. It frequently occurs that the position of the receiving-pans relative to the end of 50 the discharge-tubes needs to be adjusted. To effect this, I conveniently support the pans by having suitable lugs v formed thereon, which rest on blocks v², held in position by bolts and nuts passing through vertical slots 55 v³, formed in the supports B.

I have described one discharge-tube, but it is to be understood that four will ordinarily be employed, arranged an equidistance apart; but any desirable number may be employed. 60

In operation the material is deposited in the hopper C³ and descends into the separator, at which point it is caught by the wings d³ and by the centrifugal force is carried outward, the material discharged at the outer 65 edges of the table D², which table is cut away, leaving the passages d⁶ between its edge and

the sides of the casing, as shown in Fig. 5. The material being forced to the sides of the casing escapes into the separator below the table, and by the rapid rotation of the separator 70 the heavier particles hug the sides, and owing to the inclination of the sides of the separator, the discharges being at or near the angle of juncture of the bottom and sides, the natural tendency of the particles is to sink downward; 75 but owing to the increasing size and consequent peripheral speed (or belt-motion) of the casing the particles will not move on a meridian line, but constantly lag back from such meridian line with each successive point 80 of movement downward, and thus pass spirally downward around the inner face of the casing, partaking somewhat of this increasing motion by reason of the friction on the sides, the result of such action being that the heavier 85 particles are arranged in relation to their respective specific gravities hugging the sides of the casing and made to pass transversely across the openings in the discharge-tubes H, through which such portion as may be desired is made to pass. As they enter the discharge-tubes their movement is accelerated by the incoming water received from the supply-pipe G and through the pipes F, the water serving also to keep the discharge-tubes 90 clear. Such particles and material as are not permitted to be discharged through the slot in the discharge-tube H continue in the downward direction and are carried into the discharge-tubes K. The inclination of the bottom C' serves to force all the material below the slot in the tube H to be discharged, permitting no inert or neutral matter to remain, and thus causes a regular continuous flow 95 and movement of the particles and material 100 (pulp) in accordance with the capacity of the machine or amount fed into it. From the various tubes the material is deposited into the receiving-pans V V'.

The adjustment of the tubes having been 105 described, their operation it is deemed unnecessary to state; but it is to be understood that the openings i and h in the tubes may be set to register in such length as desired less than the full capacity by inserting the tube 110 L farther into the tube H, thus reducing the length of the slot. The size of such opening may then be diminished, as before described.

Having thus described my invention, what I claim as new, and desire to secure by Letters 115 Patent, is—

1. In a centrifugal ore-separator, the combination with a casing having collecting-passages in the sides thereof, discharge-tubes in said passages formed with lateral openings, 120 tubes provided with openings adapted to register with the openings in the discharge-tubes working in said discharge-tubes, mechanism for adjusting said interior tubes, and means for actuating said mechanism during the 125 movement of the machine, substantially as described.

2. In a centrifugal ore-separator, the combination with a casing having a discharge-tube provided with an opening, of a tube adjustably secured therein provided with an opening adapted to register with the opening of the discharge-tube, means for adjusting the interior tube consisting of a threaded coupling and a suitable threaded member stationarily supported, and means for moving the coupling to effect its adjustment during the operation of the machine, substantially as described.

3. In a centrifugal ore-separator, the combination with a casing, of a discharge-tube therein provided with a lateral opening, a tube for regulating the discharge provided with an opening adapted to register with the opening of the discharge-tube, means for adjusting said regulating-tube, a bracket, a sleeve loosely connected therewith, a connection between said regulating means and said sleeve and a screw for adjusting said sleeve, substantially as described.

4. In a centrifugal ore-separator, the combination with a supporting shaft and casing, of a discharge-tube in the casing, means for varying the size of the discharge and means for actuating said varying means, comprising a sleeve mounted on the shaft, having an inclined slot, a pin on the sleeve entering the slot, a crank connection between the sleeve and said adjusting means, and means for elevating the sleeve to cause the same to rotate on the shaft, substantially as described.

5. In a centrifugal ore-separator, the combination with a separator-casing, of means for rotating the same, separated discharge-tubes disposed around the casing, and running in the same general direction as the axis of rotation thereof provided with lateral inlet-openings, a main water-supply pipe secured to and projecting into the casing and adapted to rotate therewith, and means for conducting water from the main supply-pipe to the several discharge-tubes, substantially as described.

6. In a centrifugal ore-separator, the combination with a separator-casing, of means for rotating the same, discharge-tubes disposed at separated points around the casing and running in the same general direction as the axis of rotation, a main water-supply pipe secured to and adapted to rotate with a portion of the separator, and independent sources leading from the main supply to each of the discharge-tubes, substantially as described.

7. In a centrifugal ore-separator, the combination with a separator-casing, of means for rotating the same, discharge-tubes running in the same general direction as the axis of rotation, a main water-supply pipe secured to and adapted to rotate with a portion of the separator, and an inclined waterway leading from the main water-supply to the discharge-tubes, substantially as described.

8. In a centrifugal separator, the combination with a spindle, having a hollow upper

end, a channeled table carried by the spindle, a conical-shaped casing having independent channels formed in its sides communicating with the respective channels in the table, a water-supply pipe entering the hollow spindle and extending to the outside of the casing and connecting the tubes in the casing into which the water-channels discharge, substantially as described.

9. In a centrifugal separator the combination with a casing having a discharge-tube provided with a lateral opening, of a tube inserted in the discharge-tube having an opening adapted to register with the first-mentioned opening, and means whereby one of said tubes may be moved to vary the size of the discharge-opening, substantially as described.

10. In a centrifugal separator, the combination with a casing having a discharge-tube provided with a lateral opening, of a tube inserted in the discharge-tube having an opening adapted to register with the first-mentioned opening, and means for rotating one of said tubes to vary the size of the discharge-opening.

11. In a centrifugal separator, the combination with a casing having a discharge-tube provided with a lateral opening, of a tube inserted in the discharge-tube having an opening adapted to register with the first-mentioned opening, and means for adjusting one of said tubes vertically to vary the size of the discharge-opening, substantially as described.

12. In a centrifugal separator, the combination with a casing having a discharge-tube provided with a lateral opening, of a tube inserted in the discharge-tube having an opening adapted to register with the first-mentioned opening, and means for rotating and vertically adjusting one of said tubes to vary the size of the discharge-opening, substantially as described.

13. In a centrifugal separator, the combination with a casing, of a discharge-tube therein, a clamp for the discharge-tube having a flange thereon, a tube within the discharge-tube, a clamp on the inner tube, a flange connection between the clamp, a link connecting the clamp with the inner tube, a collar with which the opposite end of the link is connected and means for adjusting the collar to rotate the said inner tube, substantially as described.

14. In a centrifugal separator, the combination with a frame and a separating-casing, of a spindle carrying the casing, a collar on the spindle, having a pin thereon, an inclined shoulder on the spindle with which the pin engages, a pivoted yoke for moving the collar, means for moving the yoke, and an adjustable discharge-regulator actuated by the movement of the collar, substantially as described.

15. In a centrifugal separator, the combination with a casing, of a spindle therefor, a

collar on the spindle, discharge-tubes for the casing, tubes entering said discharge-tubes, connections between one of the tubes and the collar, and means adapted to engage an inclined way on the collar for rotating the same independently of the spindle, substantially as described.

In testimony whereof I affix my signature in presence of two witnesses.

PHILIP H. SHUE.
